DRIVER'S SEAT FOR A COMMERCIAL VEHICLE

Chester J. Barecki, Grand Rapids, Mich., assignor to
American Seating Company, Grand Rapids, Mich.,
a corporation of Delaware

Filed Feb. 26, 1968, Ser. No. 10,711

Term of patent 14 years

Int. Cl. D6—01; D12—99

U.S. Cl. D15—8

FIG. 1

FIG. 2

FIGURE 1 is a perspective view of a driver's seat for a commercial vehicle from the rear showing my new design; and

FIGURE 2 is a perspective view of the same taken from the front of the seat.

I claim:

The ornamental design for a driver's seat for a commercial vehicle, as shown.
